TOILET SEAT HINGE

Thomas E. Smoyer, Allentown, Pa.

Application March 21, 1958, Serial No. 50,122

Term of patent 14 years

(Cl. D4—5)

Fig. 1 is a plan view of a toilet seat hinge showing my new design.

Fig. 2 is a side elevation.

Fig. 3 is a rear elevation.

I claim:

The ornamental design for a toilet seat hinge, substantially as shown.
